Search Report issued in ROC (Taiwan) Design Patent Application No. 107302089D01 dated May 17, 2019.

Primary Examiner — Derrick E Holland

(57) **CLAIM**

The ornamental design for a busbar-less solar cell, as shown and described.

DESCRIPTION

FIG. 1 is a top perspective view of the first embodiment of a busbar-less solar cell showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a back side elevation view thereof;

FIG. 7 is a front elevation view thereof;

FIG. 8 is a top perspective view of the second embodiment of a busbar-less solar cell showing our new design;

FIG. 9 is a top plan view thereof;

FIG. 10 is a bottom plan view thereof;

FIG. 11 is a right side elevation view thereof;

FIG. 12 is a left side elevation view thereof;

FIG. 13 is a back side elevation view thereof;

FIG. 14 is a front elevation view thereof;

FIG. 15 is a top perspective view of the third embodiment of a busbar-less solar cell showing our new design;

FIG. 16 is a top plan view thereof;

FIG. 17 is a bottom plan view thereof;

FIG. 18 is a right side elevation view thereof;

FIG. 19 is a left side elevation view thereof;

FIG. 20 is a back side elevation view thereof;

FIG. 21 is a front elevation view thereof;

FIG. 22 is a top perspective view of the fourth embodiment of a busbar-less solar cell showing our new design;

FIG. 23 is a top plan view thereof;

FIG. 24 is a bottom plan view thereof;

FIG. 25 is a right side elevation view thereof;

FIG. 26 is a left side elevation view thereof;

FIG. 27 is a back side elevation view thereof; and,

FIG. 28 is a front elevation view thereof.
